BASEBALL GAME DEVICE

Robert E. Baker, Williamston, Mich.

Application August 15, 1952, Serial No. 304,562

2 Claims. (Cl. 273—89)

This invention relates to game devices, and more particularly to an improved baseball game board apparatus.

A main object of the invention is to provide a novel and improved game board apparatus provided with means whereby the operations of pitching and batting a ball may be carried out on a small scale suitable for indoor play and in which scoring operations may be carried on in a manner simulating the actual playing of an outdoor baseball game, the apparatus being simple in construction, being easy to operate, and providing a substantial degree of amusement and entertainment to the players.

A further object of the invention is to provide an improved baseball game board device which is inexpensive to manufacture, which is sturdy in construction, which is arranged to provide close simulation to actual baseball plays and scoring situations, and which is relatively compact in size.

Further objects and advantages of the invention will become apparent from the following description and claims, and from the accompanying drawings, wherein:

Figure 1 is a top plan view of an improved baseball game board apparatus constructed in accordance with the present invention.

Figure 2 is a front elevational view of the apparatus of Figure 1.

Figure 3 is an enlarged fragmentary bottom plan view of a corner portion of the game board apparatus of Figure 1, showing the arrangement of the flexible cable element thereon.

Figure 4 is an enlarged cross sectional detail view taken on the line 4—4 of Figure 1.

Figure 5 is an enlarged fragmentary top plan detail view of the pitching element of the game board apparatus, showing a ball disposed in the pitching recess.

Figure 6 is an enlarged cross sectional detail view taken on the line 6—6 of Figure 1.

Figure 7 is a cross sectional view similar to Figure 6, but showing the ball-propelling spring in a released condition, with the ball about to be projected thereby toward the home plate position of the game board.

Figure 8 is a fragmentary bottom plan view of the structure shown in Figures 6 and 7.

Figure 9 is a fragmentary perspective view of the baseball game board apparatus diagonally opposite the home plate position of the board.

Figure 10 is a sectional view taken along the line 10—10 of Figure 1.

Referring to the drawings, the improved game board apparatus is designated generally at 11 and comprises a main rectangular playing board 12 provided with the upstanding marginal walls 13 and 14 of substantial height and with the opposing marginal walls 15 and 16 of lesser height, as shown in Figure 2. The board 12 is provided with a relatively thick covering of soft cloth in the stippled areas designated respectively at 17, 18 and 19, defining the relatively depressed areas 20, 21, 22, 23 and 24 in the outfield portion of the board, the base path portion 25, and the respective infield areas 26, 27, 28, 29 and 30, suitably marked off in the manner illustrated in Figure 1. The home plate position is designated at 31 and pivotally mounted at this position is the elongated bat member 32, shown in detail in Figure 4, said bat member 32 being mounted for swinging movement around a vertical pin 33 secured through the board 12 and supported on an annular bushing member 34, whereby the bat member 32 may be manually rotated

2

around the pivot pin 33 and may be swung over the home plate by a player. The area 28 represents the pitching lane and includes an aperture 35 formed in the board 12. Secured to the under surface of the board 12 is a leaf spring 36 which is provided with an upwardly curved end portion 37 which is biased by its resiliency to a position facing the home plate position 31. The area 27 around the pitcher's position is covered with the above-mentioned thick cloth padding, as shown at 38, and said padding partially overlaps the opening 35, defining a supporting rest for a ball 39 which may be disposed in the aperture in the manner illustrated in Figure 6.

The ball 39 is provided with a flattened portion 40 so that it will come to rest and remain in a stationary position without excessive rolling on the game board after being projected thereon, as will be presently described, and also to enable the pitching device to curve the ball and thus make it more difficult to hit the ball squarely with the bat member 32.

Designated at 41 is a rectangular plate member which is slidably mounted on the board 12 rearwardly adjacent the aperture 35 for movement in a direction aligned with the home plate position 31, the plate member 41 being formed with the longitudinally aligned slots 42, 42 through which extend the retaining screws 43, 43, said screws being engaged in the board 12 to fasten the plate member 41 thereto but are arranged to allow said plate member to move in the direction of the home plate position 31. As shown in Figures 6 and 7, the plate member 41 may be moved over the aperture 35 so as to overlie the edge of the curved spring element 37 and to thus retain said spring element in a depressed position, as shown in Figure 6. When the plate member 41 is moved rearwardly, the spring element 37 is released and may strike the ball 39 to propel the ball toward the home plate position 31.

The board 12 is formed with the respective apertures 44 and 45 located adjacent the rear end of the plate member 41, the aperture 44 being generally V-shaped, as shown in Figure 8. Designated at 46, 46, are respective coil springs connected at 47, 47 to the bottom surface of the board 12 and connected at their opposite ends to the rear end portions of the plate member 41, the springs extending through the arms of the V-shaped aperture 44, as shown in Figure 8, and acting to bias the plate member 41 toward its position shown in Figure 6, namely, the position wherein its forward end overlies the aperture 35. Secured to the rear end of the plate member 41 is the flexible string 49, said string passing through the aperture 45 and extending through an eye member 50, as shown in Figure 3. The string 49 then extends laterally through an eye member 51 and emerges at the right side marginal portion of the board, as shown in Figure 1, a handle 52 being secured to the string so that it may be manually pulled by a player from the right side margin of the board, as viewed in Figure 1. It will be readily apparent that with the plate member 41 arranged in the manner shown in Figure 6, when the string 49 is pulled, the plate member 41 is withdrawn rearwardly, releasing the curved spring element 37, and allowing said spring element to strike the ball 39. The ball 39 is thus propelled toward the home plate position 31, and an opposing player may then attempt to strike the ball by rotating the bat member 32 as the ball proceeds toward the batting position. To reset the pitching device, it is merely necessary to depress the curved spring element 37 and thus allow the springs 46, 46 to pull the plate member 41 forwardly into the overlapping position thereof shown in Figure 6, whereby the curved spring element 37 is retained in its depressed position until released by pulling on the string 49.

The rules for playing the game are similar to those in the conventional game of baseball and the depressed areas designate specific scoring or other situations when the ball settles in one of said depressed areas. Thus, when the ball settles in the areas 20, 21, 23 and 24, base hits are indicated, when the ball settles in the area 22 a home run may be indicated. The areas 20 and 24 may designate doubles and the areas 21 and 23 may designate triples. When the ball settles in the area 25,

the player may be entitled to a single. When the ball settles in the area 26, the batter is out, and when the ball settles on one of the padded areas 17, 27 or 28 the batter is also out. The areas 29 and 30 designate bunting areas and when the ball settles therein it may 5 represent a sacrifice bunt.

The high walls 13 and 14 are provided with padding 53 at their lower portions, and all batted balls hitting above the padding may be counted as doubles while all 10 balls hitting the padding will remain in play and the scoring will be determined by the point at which the ball stops.

The marginal portions of the board adjacent the relatively low fence portions 15 and 16 are marked off to designate foul areas and may include a plurality of areas, such as the areas 54 and 55 having different scoring 15 significance. For example, the area 54 may represent caught fouls, whereby the batter is out when the ball rests in such an area, whereas the area 55 may merely represent foul strikes. Balls which are hit over the relatively high wall elements 13 and 14 are counted as home 20 runs when in fair territory, namely, when they are within the foul lines 57, 57, as in the conventional game of baseball.

In playing the game, one player manipulates the bat 32 while the opposing player manipulates the handle 52. As above described, when the handle 52 is pulled, the pitching element 37 is released, causing the ball 39 to be propelled toward the home plate position, and the batter then attempts to strike at the ball. If the ball 30 is hit, a baseball scoring situation may be produced, as above described.

While a specific embodiment of an improved baseball 35 game board device has been disclosed in the foregoing description, it will be understood that various modifications within the spirit of the invention may occur to those skilled in the art. Therefore, it is intended that no limitations be placed on the invention except as defined by the scope of the appended claims.

What is claimed is:

1. A baseball game device comprising a rectangular unobstructed playing board, means on said board simulating a baseball field including a home plate and a pitcher's position, said board being provided with a soft cover pad having spaced, cut-out portions forming a plurality of 40 depressed scoring areas and being provided with walls along its margin, said board being formed with an aperture only at said pitcher's position, a leaf spring secured

5 to the under side of the board and having an upwardly curved end arranged to project upwardly through said aperture and being biased toward said home plate, a retaining member slidably mounted on the board and being movable over the edge of said curved end to retain said curved end in a depressed position at times, spring means biasing said retaining member toward said upwardly curved end, flexible cable means connected to said retaining member for at other times disengaging said retaining member from the curved end of said leaf spring, and an elongated bat member pivotally mounted on said board adjacent said home plate.

2. A baseball game device comprising a rectangular playing board, means on said board simulating a baseball field including a home plate and a pitcher's position, said board being provided with a relatively soft cover pad, said pad being cut away in a plurality of spaced areas thereover, to define alternating depressed scoring areas and padded areas, said board being provided with upstanding walls along its margin, said board being formed with an aperture at said pitcher's position, a leaf spring secured to the under side of the board and having an upwardly curved end arranged to project upwardly through said aperture and being biased toward said home plate, a retaining member slidably mounted on the board, means guiding said retaining member for sliding movement toward and away from overlapping relationship with respect to the free edge of said curved end, whereby to retain said curved end in a depressed position at times, spring means connecting said retaining member to said board and biasing said retaining member toward said overlapping relationship with said curved end, flexible cable means connected to said retaining member and extending under the board for at other times disengaging said retaining member from the curved end of said leaf spring, and an elongated bat member pivotally mounted on said board adjacent said home plate for swinging movement around a vertical axis.
